United States Patent Office.

WILLIAM F. SAYLES AND FREDERICK C. SAYLES, OF NORTH PROVIDENCE,
RHODE ISLAND.

Design No. 3,751, dated November 16, 1869.

DESIGN FOR A TRADE-MARK

The Schedule referred to in these Letters Patent and making part of the same.

To all whom it may concern:

Be it known that we, WILLIAM F. SAYLES and FREDERICK C. SAYLES, both of North Providence, in the county of Providence, and State of Rhode Island, have invented and produced a new Design for a Trade-Mark Label; and we do hereby declare that the following specification, taken in connection with the drawings, making a part of the same, is a full, clear, and exact description thereof.

The design for a trade-mark label herein described, and shown in the drawings, is intended as a distinctive mark for the different styles of cotton goods bleached and finished by us, and to be stamped upon the same.

It consists of two semi-elliptical border-lines, joined at their extremities by a double scroll, terminating in a Gothic point. Near each end of the transverse axis

of the elliptical figure so formed, is placed a Gothic point, of similar character with that which ornaments the ends of the long axis, but supported on each side by scroll-work. The interior space of the ellipse is occupied with the words, in plain or ornamental character, "Finished by W. F. and F. C. Sayles, Pawtucket, R. I."

What we claim as our invention, and desire to secure by Letters Patent, is—

The design for a trade-mark label herein shown and described.

WILLIAM F. SAYLES.
FREDERICK C. SAYLES.
